UNITED STATES PATENT OFFICE.

HENRY C. BRACHTL, OF CHICAGO, ILLINOIS.

DESIGN FOR A MOTOR-CASING.

59,455.

Specification for Design.

Patented Oct. 25, 1921.

Application filed January 5, 1920. Serial No. 349,613. Term of patent 7 years.

To all whom it may concern:

Be it known that I, HENRY C. BRACHTL, a citizen of the United States, residing at Chicago, in the county of Cook and State of Illinois, have invented a new, original, and ornamental Design for Motor-Casings, of which the following is a specification, reference being had to the accompanying drawing, forming part thereof.

In the drawing Figure 1 is a top perspective view and Fig. 2 is a bottom perspective view, showing my new design.

I claim:

The ornamental design for a motor casing, as shown.

HENRY C. BRACHTL.
